UNITED STATES PATENT OFFICE.

FRANK E. MARCY, OF SALT LAKE CITY, UTAH.

ROLLER-MILL.

1,309,212.

Specification of Letters Patent.

Patented July 8, 1919.

Application filed September 26, 1917, Serial No. 193,292. Renewed October 19, 1918. Serial No. 258,908.

To all whom it may concern:

Be it known that I, FRANK E. MARCY, a citizen of the United States, residing at Salt Lake City, in the county of Salt Lake 5 and State of Utah, have invented certain new and useful Improvements in Roller-Mills, of which the following is a full, clear, and exact description, reference being had to the accompanying drawings, forming a part 10 hereof.

My invention has relation to improvements in roller mills; and it consists in the novel features of construction more fully set forth in the specification and pointed out 15 in the claims.

As well understood in the art roller mills (or rod mills) belong to that class of crushing and disintegrating apparatus wherein the material is reduced to particles of the 20 desired size by means of freely moving crushing bodies in the form of longitudinally extended bars, rods, or rollers acting by impact and attrition upon the charge confined within a suitable tumbling barrel, drum, or 25 equivalent tubular container or treatment vessel rotated about a fixed axis, the opposite ends of the barrel being respectively provided with intake or feed, and discharge openings for the material. The present im- 30 provement is directed to that type of tumbling barrel or mill in which one end of the barrel is left open and unobstructed for the discharge of the material and for the direct insertion of the grinding rods into and their 35 removal from the barrel, the advantages of such open end being apparent when we remember that the prevailing type of roller mill is provided with a head at each end, and that in order to gain access to the in- 40 terior of the mill for purposes of repair or removal of worn out and kinked rods, one of the heads must be removed, thereby entailing much labor and consuming valuable time. In my improvement the interior of 45 the mill is at all times readily accessible, the construction being such that while the material is free to directly discharge through the open end, and the grinding rods are exposed to the opening at said end, they are 50 nevertheless maintained permanently in the mill. The exposure of the contents of the mill to the open end necessarily results in considerable noise, and more or less splashing of the pulp under treatment (the ma- 55 terial treated being usually wet) and one of the objects sought by the present im-

provement is to deaden the noise and prevent the splashing. A further object is to provide means at the discharge end for retaining the grinding bars or rods within the mill 60 without depending solely on the pitch or inclination of the walls of the crushing compartment, such inclination under the circumstances being reduced to a minimum degree. The retaining means aforesaid operate, in the present embodiment of my invention, to assist in building up the pulp line prior to the discharge of the finished product from the mill. A further object of the invention is to provide means for elevating 70 the finished product after leaving the crushing compartment to a point from which it can flow under a proper head to any suitable classifier operating to return the coarse sands back to the mill for further grinding or 75 treatment. A further object is to dispose suitable lifters or equivalent devices on the inner walls of the crushing compartment which shall impart a special attrition movement to the grinding rods and in a measure 80 operate to assist in keeping the rods in the crushing compartment of the mill. The invention comprises a combination of features 85 the advantages whereof will be fully apparent from the following detailed description in connection with the accompanying drawings in which—

Figure 1 represents a middle vertical longitudinal section of the mill showing my improvements; Fig. 2 is a vertical cross-section 90 on the line 2—2 of Fig. 1, one-half of the head being removed to expose the interior, and the driving gear being broken away; Fig. 3 is an inner plan view of one of the wall liner sections showing the preferred 95 form of lifter; Fig. 4 is a cross-section on the line 4—4 of Fig. 3; Fig. 5 is a similar cross-section of a wall liner section showing a modified form of lifter; Fig. 6 is a dia- 100 grammatic middle horizontal section of the barrel or drum and a single grinding rod showing the cataracting path of a released rod; Fig. 7 is a vertical cross-sectional dia- 105 grammatic view of the barrel looking from the feed toward the discharge end showing in end view the cataracting rod illustrated in Fig. 6; Fig. 8 is a side elevation of the discharge end of the barrel shown in conjunction with a sound and splash arresting housing or casing; Fig. 9 is a front elevation of 110 the housing, or a view at right angles to Fig. 8 looking toward the left; Fig. 10 is

a vertical cross-section of a barrel showing a bucket-supporting extension beyond the overflow ring over which the pulp discharges, and side elevation of the launder 5 receiving the contents of the buckets; and Fig. 11 is an end view of Fig. 10 with parts broken away.

Referring to the drawings, and for the present to Figs. 1 to 4 inclusive, 1, represents a (preferably) cylindrical container, drum, tumbling barrel, or equivalent tubular member, the same being provided with a wall liner composed of a series of sections 2, the sections having formed thereon (or se- 15 cured thereto) suitable ribs 3 which serve as lifters for the grinding rods or rollers 4. In the present embodiment of my invention the lifters 3 are warped, that is to say, they are disposed at an incline to the elements of 20 the periphery of the drum, and necessarily, assume a spiral form where the drum is cylindrical. The lifters are so inclined that the ends nearest the feed end of the drum are in advance of, or precede the ends near- 25 est the discharge end of the drum in the normal rotation of the drum (see arrows, Figs. 1, 2, 6, 7). This would bring the ends of the lifters which are nearest the feed end of the drum below the ends which are nearest 30 the discharge end on the descending half or side of the drum periphery (see arrow Fig. 1) while on the ascending side of the drum the feed ends of the lifters would be above the discharge ends (Figs. 2, 7), the grind- 35 ing rods 4 being of course lifted by the lifters only on their upward sweep. The action of the warped lifters on the rods is such as to keep the rods in the mill, as later herein more fully described. The lifters ter- 40 minate some distance from each end of the liner sections as fully illustrated in the drawings. The feed end of the mill is closed by a head or cover 5 provided with a hollow feed or intake trunnion 6 to which the pulp 45 is conveyed by a scoop-feeder 6', or otherwise, as well understood in the art, the head being protected by the end liner 7 against which bear the adjacent terminals of the wall liner sections 2. The drive gear 8 in the 50 present instance is at the feed end of the barrel.

In the present embodiment of my invention the open discharge end of the barrel or drum is provided with an annular frusto- 55 conical diaphragm or ring 9, the pitch of the inner walls whereof is anywhere from forty-five (45) to sixty (60) degrees to the base of the frustum or to a transverse plane through the axis of the drum, said walls sloping out- 60 wardly from the crushing compartment C of the drum and inwardly toward the axis of the drum as shown to best advantage in Fig. 1 of the drawings. In other words the base of the frustum faces the inside of the drum. 65 The said ring 9 has a two-fold function. In

the first place it operates to build up the pulp line in the mill, and in the second place it assists in maintaining the grinding rods in the mill. The mill or drum is slightly pitched (the horizontal being indicated by the line h in Fig. 1) so as to cause the walls of the crushing compartment to incline upwardly from the feed to the discharge end, said inclination, together with the ring 9 and the lifters 3 coöperating to maintain the rods within the mill. It will be noted that the pitch of the mill is but slight; yet circumstances might arise where even this slight pitch could be dispensed with and the drum rotated about a horizontal axis. In that event the main reliance for keeping the grinding rods within the mill would have to be placed on the lifters 3 and on the diaphragm or ring 9. The finished product obviously discharges over the bottom portion 85 of the inner edge of the ring 9, the level of the pulp line being indicated by the reference letter x . Without the presence of the ring 9 the pulp line would necessarily drop. Thus the ring serves to build up the pulp 90 line and permits the charge to be subjected to the grinding action of the rods (or their equivalent) for a somewhat longer period of time than would be the case were the ring dispensed with and the pulp line allowed to 95 drop. The ring of course in no wise interferes with the free introduction of the grinding rods into, or their removal from, the crushing compartment of the mill, the presence of the ring not materially reducing 100 the size of the opening at the discharge end of the mill. In fact the ring 9 may be considered as a flange directed inwardly or projecting toward the axis of the mill a sufficient distance from the walls of the crushing compartment to build up the pulp line, and to assist in a measure in preventing the rods from working out of the mill. As seen to best advantage in Fig. 2 (see also Fig. 7), the number of grinding rods employed is 110 sufficient to bring the center of gravity of the mass of rods opposite the opening to which they are exposed at the discharge end of the mill, the rods released from the lifters 3 with the rotation of the mill tumbling 115 or being precipitated in paths opposite said opening and above the lower portion or half of the flange 9 the inner edge of which defines the available opening through which the finished product is free to flow. The center of gravity in the present instance is obviously near the center of the figure representing the cross-section of the mass of rods. 120 The preferred form of lifter 3 is that shown in the figures referred to above, but I do not wish to be understood as limiting myself to this or any other specific form of lifter. In Fig. 5 for example I show a wall liner section 2' with a lifter or rib formation 3' somewhat less rounded and 130

more angular in cross-section than the lifter 3. Other forms might be devised as clearly obvious to those skilled in the art.

In a mill of the character described, that is, a mill in which the discharge end is open and everything in the mill is exposed, the operation is necessarily attended with considerable noise, and more or less splashing of the pulp. To deaden the sound of the 10 grinding action and arrest the splashing I may resort to the use of a stationary housing or casing 10 by which the discharge end of the drum 1 is loosely received and within which it terminates, access to the interior of 15 the housing and hence to the interior of the mill being had through suitable doors D in the front wall of the housing as shown in the modified structure illustrated in Figs. 8 and 9. No special construction of housing is 20 claimed, that here shown being illustrated conventionally. The application of a housing to an open end type of mill however is believed to be new and I accordingly claim this as one of the novel features of the present 25 invention. Where a housing is employed, the upper end of the launder 11 which receives the finished product terminates in the housing.

As well understood in the art, the coarser 30 sands of the finished product of a grinding mill are usually returned to the mill for further grinding or regrinding. This return is generally effected through any well known type of classifier into which the overflow or pulp from the mill is first discharged. A launder generally conducts the pulp from the point of overflow of the mill to the classifier; and since such a launder should have sufficient pitch to impart the 35 desired flow or velocity to the pulp after the latter leaves the mill, the point of discharge from the mill should be as high as possible to give the pulp the proper head. In a mill having a trunnion overflow the 40 head is manifestly much greater than in the case of a mill with an open discharge end where the pulp line or overflow is low or near the bottom of the mill and considerably below its rotation axis. This loss of 45 head resulting from the use of a mill having an open discharge end is obviously a disadvantage when the mill is used under the related circumstances, but the objection in that regard is readily overcome by equipping the mill with suitable means for elevating the pulp to a plane above the rotation axis of the drum after the pulp has passed over the edge of the flange or ring 9. One 50 form of such means is illustrated in the modified structure shown in Figs. 10 and 11. In this modification the shell or peripheral wall of the drum 1' projects or extends beyond the ring 9, the said extension terminating 55 in an inner flange 12 and having disposed on the inner face thereof and adjacent 60

to the overflow edge of the ring, a series of buckets 13 which successively scoop or pick up the pulp as it flows over the edge of the ring at the bottom of the drum, the contents of the buckets being discharged at a point 70 above the rotation axis of the drum into a box or receptacle 14 forming the upper terminal of a launder 15 which conducts the finished product to a suitable classifier (not shown) from which the coarse sands are returned to the mill for regrinding.

The grinding operation of the mill does not differ materially from that of other mills of the general class or type here referred to, the pulp being fed to the crushing compartment of the mill through the hollow trunnion 6, the material being ground by the crushing bodies 4 in said compartment. The finished product is discharged through the open discharge end of the mill, the pulp line being maintained substantially at the level α (Fig. 1), the stream flowing over the lower edge of the ring or flange 9 as indicated by the arrow in Fig. 8 where the pulp is shown as being 80 discharged into the launder 11. In a roller mill employing warped lifters such as 3 it is found that the end of the grinding rod 4 which is nearest the open discharge end of the mill is the first to leave or drop from the lifter by which it was picked up, the end of the rod thus released tending to swing inwardly or into the mill as indicated by the arrow a in the diagrammatic view in Fig. 6, the opposite end of the rod or that nearest the feed end being still supported on the lifter and serving as a fulcrum about which the released end tends to oscillate. Thus the rod assumes an inclined position as shown by the bottom dotted illustration in 90 Fig. 6; and when finally the end of the rod nearest the feed end of the mill is released or drops, the rod will cataract or roll down the mass of rods in the direction of the arrows a' , a' , (Fig. 6), that is to say in a direction parallel to itself and toward the feed-end liner 7 rather than toward the open 95 end of the mill. The successive positions of the descending or cataracting rod are shown respectively in plan and end views 100 in Figs. 6 and 7. The warped lifters thus tend to maintain the grinding rods in the mill during the rotation of the mill. In addition to the warped lifters we have the pitch of the mill which also assists in keeping the rods in the mill; and finally we have the inclined inner wall of the ring 9 which tends to direct any rod back into the mill should the adjacent end of the rod impinge 105 against said inclined wall. It is seldom that a rod would cataract or tumble in such a way as to project beyond the edge of the ring 9; but should it do so, it would immediately slip back into the mill. We thus 110 have in the present embodiment of my in- 115

120
125
130

vention three agencies which contribute to keeping the grinding rods within the mill, to-wit, (1) the warped lifters, (2) the pitch of the mill, and (3) the conical flange or ring 9. By terminating the lifters 3 a suitable distance from the feed end of the mill, that is to say from the discharge end of the feed trunnion 6, so as to allow the grinding rods (which extend substantially the length 10 of the crushing compartment C) to project beyond the lifters, I am enabled to deliver the pulp well to the ends of the rods in all positions, the pulp too having more freedom of flow where the lifters terminate a few 15 inches from the end liner 7. To prevent the lifters from throwing the grinding rods into the air they should not project too far radially into the crushing compartment, and in practice I find that a lifter having the 20 thickness and contour shown in Fig. 4 gives excellent results in practice. The grinding rods being permanently retained in the crushing compartment of the mill, makes it perfectly safe to employ in conjunction with 25 the mill a housing such as 10 (Figs. 8, 9,) or the arrangement of buckets 13 and launder 15 shown in Figs. 10 and 11, there being no danger of the rods being projected outwardly and injuring any of these parts, or 30 becoming jammed in the housing. Obviously, the construction is susceptible of many changes without involving a departure from the spirit of the invention. For example, the size of the discharge opening 35 of the mill need not be as shown. The same may be varied by varying the width of the diaphragm or flange 9 relatively to the diameter of the crushing compartment C. By reducing the width of the flange the available opening will be correspondingly increased. By increasing the width of the flange the available opening will be correspondingly reduced; but in no sense must the discharge opening be reduced to the 40 45 point where it would interfere with the free introduction of the grinding rods into, or their removal from the mill; or to the point where the rods would no longer tumble or roll in front of, or be exposed to, said opening; or to the point where the material was no longer free to discharge from the ends of the rods through the opening; or to the point where a full inspection of the grinding operation in the mill while running was 50 55 no longer possible. Such an undue reduction in the size of the discharge opening is foreign to the present invention. Again, the flange need not necessarily be frusto-conical, or as shown. Neither do I wish to be understood as limiting myself to any particular means for causing an inward deflection of the grinding rods at the beginning 60 65 of their tumbling movement to cause the rods to roll away from the open end of the mill. Any suitable means capable of so

deflecting the rods are contemplated by the present invention. The foregoing changes are mentioned by way of example; others may suggest themselves to the skilled mechanician. Features shown but not alluded to are well understood in the art and require no description in the present connection. 70

Having described my invention what I claim is:

1. In a mill of the character described, a 75 tumbling barrel having a feed end and a normally open discharge end, a plurality of freely moving loose grinding rods in the barrel extended longitudinally substantially the length of the barrel and directly 80 removable through said open end, and means in the barrel for imparting to the rods an inward deflection or oscillation at the beginning of their tumbling movement with successive rotations of the barrel. 85

2. In a mill of the character described, a tumbling barrel having a feed end and a normally open discharge end, a plurality of freely moving loose grinding rods in the barrel extended longitudinally substantially 90 the length of the barrel and directly removable through said open end, and suitable formations on the inner walls of the barrel for lifting the rods and subsequently releasing the same with each rotation of the 95 barrel, and imparting to the rods at the moment of their release an inward oscillation or away from the open end of the barrel.

3. In a mill of the character described, a 100 tumbling barrel having a feed end and a normally open discharge end, longitudinally extended grinding rods therein, and means in the barrel for lifting the rods and subsequently releasing them first at the ends 105 nearest the discharge end and then at the ends nearest the feed end of the mill, to cause the rods to roll away from the discharge end.

4. In a mill of the character described, a 110 tumbling barrel having a feed end and an open discharge end, a diaphragm or flange at the discharge end projecting toward the axis of the barrel and defining the opening through which the material may discharge, a plurality of longitudinally extended grinding rods in the barrel, and means secured to said barrel for causing the rods to be lifted with the rotation of the barrel and subsequently be caused to tumble in 115 paths opposite to the discharge opening defined by the flange aforesaid. 120

5. In a mill of the character described, a tumbling barrel having a feed end and an open discharge end, an inwardly projecting 125 flange at the discharge end defining the opening through which the material may flow, longitudinally extended loose, freely moving grinding rods in the barrel massed to bring the center of gravity of the body 130

of rods opposite the discharge opening defined by the flange, and means for causing the rods to tumble in paths opposite said opening with the rotation of the barrel.

5 6. In a mill of the character described, a tumbling barrel having a feed end and an open discharge end, an inwardly projecting frusto-conical flange at the discharge end having its base facing the crushing compartment and its smaller and outer end defining the opening through which the material may flow, longitudinally extended loose, freely moving grinding rods in the barrel massed opposite the flange and opposite the discharge opening defined thereby, the inclined walls of the flange operating to direct into the mill any rod impinging against said walls.

10 7. In a mill of the character described, a tumbling barrel having a feed end and an open discharge end, an inwardly projecting flange at the discharge end defining the opening through which the material may discharge, longitudinally extended loose, freely moving grinding rods in the barrel massed opposite the flange and opposite the discharge opening defined thereby, and means in the barrel for causing the rods to tumble in paths opposite the discharge opening aforesaid.

15 8. In a mill of the character described, a tumbling barrel having a feed end and an open discharge end, an inwardly projecting flange or diaphragm at the discharge end defining the opening through which the material may flow, a plurality of freely falling grinding rods in the barrel massed between the opposite ends thereof and extending substantially the full length of the barrel, and means in the barrel for causing the rods to tumble in paths opposite the discharge opening, upon rotation of the barrel.

20 9. In a mill of the character described, a tumbling barrel having a feed end and a normally open discharge end, longitudinally

extended loose and freely moving grinding rods in the barrel extending substantially the length of the crushing compartment of the barrel, the material being discharged from the ends of the rods directly exposed 50 and opposite to the discharge opening of the barrel.

10 10. In a mill of the character described, a tumbling barrel, a plurality of longitudinally extended grinding rods therein, one 55 end of the barrel being open for the discharge of the material from the ends of the rods, and for the exposure of the rods and their direct removal from the mill, and lifters on the inner walls of the barrel for 60 releasing the end of a rod nearest the discharge end of the mill in advance of the opposite end of the rod, and to impart to the rod at the moment of said release a swing inwardly or away from the discharge 65 end, whereby the tendency of the rod in its precipitation is to remain in the mill.

11. In a mill of the character described, a barrel rotatable about its longitudinal axis and having a feed end and a normally 70 open discharge end disposed about said axis, a plurality of tumbling rods in the barrel extended longitudinally substantially the length of the barrel and directly removable through said open end, devices contiguous 75 to the open end of the barrel operating periodically below the pulp line or plane of discharge of the outflowing material for catching said material, and subsequently elevating and discharging the same above said plane, 80 and a diaphragm or flange disposed adjacent said devices on the side facing the crushing compartment of the barrel to protect said devices from the rods.

In testimony whereof I affix my signature, 85 in presence of two witnesses.

FRANK E. MARCY.
